United States Patent

Des. 237,960
Patented Dec. 9, 1975

237,960

AUTOMOBILE HOOD

Robert J. Whitehead, Orange, Calif., assignor to Nissan Motor Corporation in U.S.A., Gardena, Calif.

Filed July 24, 1974, Ser. No. 491,311

Term of patent 14 years

Int. Cl. D12—16

U.S. Cl. D12—173

FIG. 1 is a perspective view of an automobile hood showing my new design;

FIG. 2 is a top plan view thereof;

FIG. 3 is a side elevational view thereof taken from the opposite side of FIG. 1; and

FIG. 4 is a vertical sectional view thereof taken along line 4—4 of FIG. 2.

I claim:

The ornamental design for an automobile hood, as shown.
